UNITED STATES PATENT OFFICE.

MILTON C. POWELL, OF RALSTON, NEBRASKA.

DESIGN FOR A BUILT-IN KITCHEN-CABINET.

46,348.

Specification for Design.

Patented Sept. 1, 1914.

Application filed January 30, 1914. Serial No. 815,552. Term of patent 14 years.

To all whom it may concern:

Be it known that I, MILTON C. POWELL, a citizen of the United States, residing at Ralston, in the county of Douglas and State of Nebraska, have invented a new, original, and ornamental Design for a Built-In Kitchen-Cabinet, of which the following is a specification, reference being had to the accompanying drawing, forming a part thereof, which shows a front elevation of the cabinet 1 in closed condition and provided

with a "trim," border, or facing 2, where the cabinet joins the wall 3, into which the cabinet is set.

I claim:

The ornamental design for a built-in kitchen cabinet, as shown.

MILTON C. POWELL.
